KEY CONTAINER

Earl C. Nelson, Detroit, Mich.

Application August 2, 1938, Serial No. 222,665

3 Claims. (CL 70—456)

The present invention relates to improvements in containers adapted for keys and the like and provides a device of this character whereby two keys are effectively accommodated in a manner so that they are completely covered when not in use thereby preventing injury to the pocket, purse or otherwise.

One of the objects of the invention is to provide a compact case in which one of the keys is secured to one side portion of the case and the other key being likewise secured to the opposite side portion of the case.

Another object of the invention is that each of the keys are quickly identified and that by sliding a knob disposed upon the exterior of the case the key preferred is moved outwardly, still remaining secured to the case may be very conveniently used with the case acting as a sturdy handle for the key.

With the foregoing in mind, it will become readily apparent that the invention possesses further advantages, all of which will be clearly revealed during the course of the following detailed description, illustrated throughout the accompanying drawing, and more fully pointed out in the appended claims.

Figure 1 is a top plan view of the case only, and Figure 2 is a side elevation thereof.

Figure 3 is a section taken upon line 3—3 of Figure 2, and exposing one of the keys and other elements in the case.

Figure 4 is a side elevation of the case with both keys maximumly extended therefrom and ready to use.

Figure 5 is a section taken upon line 3—3 of Figure 2 with the key and other elements omitted.

Figure 6 is a section upon line 6—6 of Figure 2.

Figure 7 is an enlarged section taken upon line 7—7 of Figure 1.

Figure 8 is a superenlarged sectional assembly of one of the button screws and the sleeve therefor.

Figure 9 is a superenlarged view of one of the button screws.

Figure 10 is a superenlarged view of one of the sleeves.

Figure 11 is a superenlarged side elevation of one of the special springs employed.

Figure 12 is a superenlarged sectional assembly of the complete device taken through the horizontal center thereof and showing both keys in position therein when normally not in use.

The invention consists of case 1 which may be composed of any suitable material but preferably composed of the more recent plastic qualities, and

with particular reference to Figures 1, 7, and 12 it is decisively clear that elongated slot 2 is arranged within each of the sides of said case, and referring to Figures 5 and 6 it is obvious that elongated channel 3 is also provided where indicated and both of said channels extending parallel with respect to the case.

The conventional type keys are designated A and B respectively, and specially designed button screw 4 is provided and is adapted to pass through the usual aperture of key A, while similar button screw 5 likewise passes through the aperture of key B.

Referring now to Figures 8 and 10 it is clear that internally threaded sleeve 6 is provided so as to accommodate button screws 4 and 5 respectively, and square head 7 of said sleeve is of such proportions so as to slidably engage either one of channels 3 of the case with button screws 4 and 5 threadedly engaging their respective sleeves 6, and with reference to Figures 11 and 12 it is clear that special spring 8 is provided and has apertures 9 within both sides thereof for passage of sleeve 6 and the respective button screws 4 and 5, and in this manner the frictional tension of said springs exerted continuously against the walls of the passages within case 1 permit both of keys A and B to slide outwardly by virtue of slots 2 and as indicated in Figure 4 and to retain them in this position, and likewise in the closed position as in Figures 3 and 12.

In conclusion it is to be understood that the disclosure herewith is merely illustrative of the general principle sought to be protected by Letters Patent, and that any slight modification during any probable further development of the device for the market would invariably fall within the scope of the claims.

Having thus fully described my invention, what I claim as new is:

1. In a key container, a unitary case structure, said structure comprising a body, a pair of longitudinally extending channels within said body, said channels in spaced apart relation and having one of their ends closed and the closures being in opposed relation, a groove within the floor of each of said channels and parallel with the same; a stud and a nut therefor, the head of said stud adapted to slidably engage one of aforesaid grooves, a U spring interposed intermediate said stud and nut and a conventional key positioned within said spring.

2. In a key container, a unitary body, a pair of spaced apart longitudinally extending channels within said body and having one of their

ends closed and the closures being in spaced apart relation, a groove within the floor of each of said channels and parallel thereto, key holding means comprising a pair of studs and a nut for each of said studs, the head of said studs adapted to slidably engage the respective aforesaid grooves, a U spring interposed between each of said studs and nuts and a conventional key adapted to be positioned within each of said springs.

3. In a key container, a unitary body, a pair of key holding units, each of said units comprising a stud and a nut therefor, a U spring interposed between said stud and nut and a conventional key adapted to be positioned within said spring; means within aforesaid body whereby said key holding units slidably coact with the body for the intended purpose.

EARL C. NELSON.
